CHARLES M. ABERCROMBIE, OF BRIDGEPORT, CONNECTICUT, ASSIGNOR TO WHEELER & WILSON MANUFACTURING COMPANY, OF BRIDGEPORT, CONNECTICUT, A CORPORATION OF CONNECTICUT.

SEWING-MACHINE NEEDLE-BAR CONNECTION.

SPECIFICATION forming part of Letters Patent No. 769,039, dated August 30, 1904.

Application filed September 30, 1903. Serial No. 175,231. (No model.)

To all whom it may concern:

Be it known that I, CHARLES M. ABERCROMBIE, a citizen of the United States, residing at Bridgeport, in the county of Fairfield and State 5 of Connecticut, have invented a certain new and useful Improvement in Sewing-Machine Needle-Bar Connections, of which the following is a full, clear, and exact description.

The object of this invention is to provide a joint for the connection of the needle-bar and its reciprocating device in that form of sewing-machines in which the needle-bar is mounted in an oscillating gate or frame for the formation of a zigzag stitch. Heretofore 10 it was common to provide some sort of universal joint or ball-and-socket joint for this connection; but there is unnecessary and oftentimes undesirable flexibility and undue wear in such universal or ball-and-socket 15 joint, and I seek by the present invention to produce a joint or connection which while admitting of the necessary reciprocation of the needle-bar and the oscillation of its carrier or frame or gate will avoid the objections to 20 prior constructions.

The invention consists of what might be called for want of a better name a "short stud-shaft" affixed to the needle-bar and projecting laterally therefrom on opposite sides 25 thereof, combined with a hollow bearing-piece fitted on said stud-shaft and having a sliding connection with the crank-link or other device by which motion is imparted from the needle-shaft.

In the accompanying drawings, illustrating 30 the invention, in the several figures of which like parts are similarly designated, Figure 1 is a side elevation of the needle-bar carrier, needle-bar, and connection in full lines, with 35 sufficient of the sewing-machine head in dotted lines to show the application of the improvement, the carrier being vibrated to the extreme right-hand position. Fig. 2 is a view similar to Fig. 1, with the carrier vibrated to 40 the extreme left-hand position. Fig. 3 shows a portion of the needle-bar with the connection in cross-section, the plane of section be-

ing at right angles to the view shown in Figs. 1 and 2. Fig. 4 is a view similar to Fig. 3, the plane of section being at right angles to Fig. 3. Fig. 5 is a perspective view of the connection detached. Fig. 6 is a perspective view of the bearing. Fig. 7 is a perspective view of the stud-shaft; and Fig. 8, a perspective view of the set-screw for securing the stud-shaft on the needle-bar, these three parts shown in Figs. 6, 7, and 8 constituting the improvement. 55

The carrier, frame, or gate 1 is adapted to be pivoted at 2 to the head of the machine 60 and has bearings 3 and 4 for receiving the needle-bar 5. The device 1 is provided with a transverse slot 6, through which extends a headed screw 7 into the head of the machine to permit of the oscillation of the 65 frame and at the same time prevent the frame from swinging outward away from the head of the machine. As shown in dotted lines, 8 is a lever pivoted to the frame at 9 and extending to a cam or other suitable device for 70 oscillating the frame. All of these previously-described parts are substantially the same as employed in the well-known Wheeler & Wilson sewing-machine.

The improvement consists of a cylindrical 75 stud-shaft 10, perforated centrally, so as to be slipped upon the needle-bar and held thereon in given position by means of a set-screw 11, entered from one end thereof, and thus exposed outside of the bearing. Upon this stud-shaft is mounted a bearing-piece 12, perforated transversely to receive the stud-shaft before it is applied to the needle-bar and also perforated at right angles or vertically in alinement with the perforation in the stud-shaft, so as to be slipped upon the needle-bar. 80 The vertical perforation in the bearing-piece 12 is of greater diameter than the needle-bar, so that a relative rocking motion between the needle-bar and its stud-shaft on the one hand and said bearing-piece on the other hand occurs as the gate oscillates. The tongue 13 extends outwardly from the bearing, and it is 85 adapted to have a sliding connection with a

socket-piece 14 on the crank-link 15 or other device connected with the needle-actuating shaft (not shown) of the sewing-machine for imparting reciprocating motion to the needle-bar.

Obviously as the needle-bar is reciprocated and its carrier, or frame, or gate oscillated the stud-shaft 10 has a rocking motion in the bearing 12 as the tongue 13 works back and forth in the socket member 14, and thus the bearing-piece 12 and its tongue 13 are maintained in true alinement with the needle-bar-reciprocating device, and hence there is no cramping of the joint and comparatively little, if any, wear of the parts. Moreover, a joint or connection is provided which is of simple and durable construction and its parts readily accessible and the whole capable of ready adjustment.

20 What I claim is—

1. A needle-bar connection for sewing-machines, comprising a stud-shaft perforated transversely so as to be slipped upon a needle-bar, with its ends projecting from opposite sides of said needle-bar, means for securing said stud-shaft in place, and a bearing-piece perforated at right angles to movably engage the stud-shaft and needle-bar, and also having a tongue for connection with a needle-bar-actuating mechanism.

2. The combination of a needle-bar carrier, frame or gate adapted to be oscillated, a needle-bar mounted therein, means to reciprocate said needle-bar, and a connection between the needle-bar and the means for reciprocating it, comprising a stud-shaft mounted upon the needle-bar and projecting laterally from opposite sides thereof, a bearing-piece mounted upon said stud-shaft, and means for slidably connecting the bearing-piece with the needle-bar-reciprocating device whereby a relative rocking motion between the stud-shaft and

needle-bar and the bearing-piece occurs as the frame oscillates.

3. The combination of a needle-bar carrier, frame or gate, means to oscillate it, a needle-bar mounted in said gate, means to reciprocate it, and a connection between the needle-bar and its reciprocating means, comprising a cylindrical stud-shaft perforated transversely so as to be slipped and secured upon the needle-bar, a bearing-piece perforated horizontally and loosely applied to the stud-shaft and having a vertical perforation of greater diameter than the needle-bar to permit a relative rocking motion of the needle-bar and stud-shaft as the frame oscillates, and a projection on the bearing-piece for effecting a sliding connection with the needle-bar-reciprocating means.

4. The combination of a needle-bar carrier, frame or gate, means to oscillate it, a needle-bar mounted in said gate, means to reciprocate it, and a connection between the needle-bar and its reciprocating means, comprising a cylindrical stud-shaft perforated transversely so as to be slipped upon the needle-bar, a setscrew for fixing the stud-shaft on the needle-bar, a bearing-piece perforated horizontally and loosely applied to the stud-shaft and having a vertical perforation of greater diameter than the needle-bar, to permit a relative rocking motion of the needle-bar and stud-shaft as the frame oscillates, and a tongue on the bearing-piece for effecting a sliding connection with the needle-bar-reciprocating means.

In testimony whereof I have hereunto set my hand this 25th day of September, A. D. 1903.

CHARLES M. ABERCROMBIE.
